Patented Aug. 9, 1921.

UNITED STATES PATENT OFFICE.

ELMER J. BLISS, OF BOSTON, MASSACHUSETTS.

ORTHOPEDIC LAST.

1,387,038.

Specification of Letters Patent. Patented Aug. 9, 1921.

Application filed October 20, 1919. Serial No. 332,001.

To all whom it may concern:

Be it known that I, ELMER J. BLISS, a citizen of the United States, and resident of Boston, in the county of Suffolk and State 5 of Massachusetts, have invented certain new and useful Improvements in Orthopedic Lasts, of which the following is a specification.

This invention relates to lasts for the manufacture of boots and shoes and is intended to provide a construction of last which will insure correct relative locations of the inside ball, outside ball portion and the heel which form the three main supporting points of the human foot, or as it 15 may be termed the base or tripod of the foot.

The human foot considered as a supporting base or pedestal for carrying the weight 20 of the body comprises essentially a three-point support or tripod including the heel, the inside ball and the outside ball portion.

In common practice the makers of lasts for use in the manufacture of ready made shoes, 25 while recognizing or prescribing certain standards of length and width of last block, have usually left to the individual judgment of the workman turning the last the precise location or relationship of the outside 30 and inside ball portions with reference to each other and to the rear or heel end of the last. Now even if the last has the correct length and width for a given size foot it may still be incorrect to a very considerable 35 extent in respect to the relative locations of the outer and inner ball portions to each other and to the heel thereby causing discomfort and even serious injury to the foot wearing a shoe containing these incorrect 40 measurements of the foot tripod.

The present invention overcomes this serious difficulty by providing a gaging device adapted to be secured to the bottom of the last block and so proportioned as to indicate with reasonable exactness the correct 45 locations of these three points in relation to one another. The device is useful not only in indicating the proper relationships of these points in a given length or width of 50 last, but also to indicate plainly any alteration in these measurements which may occur through the shrinking or the swelling of the last block after it has been completed. In short, to whatever cause it may be due, 55 too long an arch as well as too short an arch measurement on either the outside or

the inside of the last frequently results from the haphazard system of making the lasts or of using a last that was originally made with correct dimensions which have been 60 changed by the drying or swelling of the wood.

To this end the present invention comprises generally speaking a last block provided with a fixed gage of pre-determined 65 dimensions so formed as to indicate the correct locations of the ball on opposite sides of the last with relation to the heel, such device being preferably made of a material that is not subject to shrinking or expansion 70 under conditions of moisture. Incidentally the gage may be provided with a vertical extension indicating the correct form or curvature that should be given the heel portion of the last in the central vertical plane 75 at the rear end of the heel. These and other features of the invention will be more particularly explained in this specification and will be defined in the claims hereto annexed.

The invention is applicable to the old solid one piece last block that is integral from heel to toe as well as to the hinged last blocks in which the heel portion is hingedly 80 connected to the fore-part.

In the accompanying drawings I have illustrated a simple and convenient form embodying the invention as applied to a hinged last block in which;

Figure 1 is a bottom plan view of a hinged 90 last block containing the invention.

Fig. 2 is a side elevation partly in section of the construction shown in Fig. 1.

In the practice of my invention as illustrated in the drawings, the last block comprising, in this case, the fore-part *a* and the heel portion *b* hingedly connected therewith is grooved to receive the gaging device which is to define or indicate the location of the ball portions of the opposite sides of 100 the last with relation to the rear end of the heel, the grooves being made in accordance with the gaging device supplied for any particular size of last.

The gaging device itself comprises essentially a longitudinal member *d* united to a transverse member *d'* at its forward end, the transverse member being suitably disposed so that its opposite extremities will fall at those points of the last where the 110 ball on the opposite sides of the last should be formed when the rear end of the gage

is suitably attached to the heel portion of the last.

The measurements of the gage will be based upon standard measurements derived 5 from measurements of a large number of feet of a given size so as to indicate the mean or average measurements for a given length of foot. It will, of course, be understood that different feet of the same size 10 will vary to some extent in respect to the tripod measurements, that is, the measurements from the heel to the two ball portions, but if the average of these measurements is taken it will be found that the variations 15 will not be of sufficient magnitude to cause any material injury or discomfort in the case of an ordinary foot that varies from the standard measurements adopted.

The longitudinal member is provided at 20 its rear end with a vertical extension d^2 which preferably is given the correct curvature that should be given to the rear end of the heel portion of the last block.

In order to permit the movement of the 25 heel block on its pivotal joint connection with the fore-part it is necessary to subdivide the longitudinal member d into two parts co-incident with the vertical plane separating the fore-part from the heel part 30 at the bottom of the last as indicated at d^2 , and the two portions of the gage in such case are set so that their adjacent ends abut when the last is in extended position for normal use in the shoe.

35 In the case of a solid one piece last block, of course, such sub-division is not required. The gages are of course made as rights and lefts since the transverse member d' will usually extend at an oblique angle to the 40 longitudinal member.

When the gage is set with the rearward extension d^2 in position to define the heel end of the last block the opposite ends of the transverse member will coincide with the 45 inside ball a^2 and the outside ball a' thus securing complete standardization of these measurements from the rear of the heel. The heel plate or wear plate c usually provided on the heel portion of the last is, of 50 course, sub-divided into two parallel portions as indicated in Fig. 1.

If after the last is completed any change 55 takes place in the dimensions by the swelling of the wood it will result in the formation of a noticeable gap at the dividing line d^2 . In case there is shrinkage of the wood forming the last block the abutting ends of the longitudinal member d will prevent the heel from being extended to its 60 full normal position and thereby equally indicate a change of measurement and thus serve as a warning against the further use of the last while in that condition. In short, not only does the gaging device form an accurate means for standardizing the location

of the inside ball portions of the last, but also serves to indicate any substantial change in these measurements due to change in the last.

It is, of course, desirable in order to get 70 the full efficiency of the gaging device that it should be made of some material like metal for example which will not swell and shrink with changes in moisture.

The gage member may be secured in the 75 last in any suitable manner as by forcing it tightly into the grooves for its reception in the bottom of the last or by pinning or otherwise.

What I claim is:

1. A last for the manufacture of shoes embracing in its construction a last block and a ball determining gage member affixed to the bottom of said last block and comprising a longitudinal member extending a 85 pre-determined distance from the rear or heel end of the block to the ball portion of the fore-part of the last, and a transverse member united to said longitudinal member and having its opposite ends located to define the correct location of the outside ball and the inside ball portions of the last, substantially as described. 90

2. A last for the manufacture of shoes embracing in its construction a last block, a 95 gaging device secured to the bottom of the last block and constructed with three gaging points disposed in proper relationship to each other to indicate the correct relative locations according to predetermined measurements of the points forming the tripod of the foot, substantially as described. 100

3. An orthopedic last embracing in its construction a last block, a gaging device secured to the bottom thereof and comprising a longitudinal member extending from the rear of the heel to the middle part of the ball line, and a transverse member united therewith and located to coincide with the correct transverse ball line of the 110 foot, substantially as described. 105

4. A gaging device for attachment to a last embracing in its construction a longitudinal member provided at one end with an upward extension to gage the heel portion of 115 the last, and having at its other end a transverse member rigidly united therewith whose ends are positioned to indicate the correct points for locating the inside and the outside ball portions of the last, substantially as described. 120

5. A gaging device for application to lasts embracing in its construction a longitudinal member whose rear end is adapted to be secured in the heel end of the last and a transverse member united with said longitudinal member at the front end thereof and extending obliquely to the longitudinal member, the ends of said transverse member being dimensioned to indicate the correct 125 130

locations for the inside and outside ball portions of the last according to predetermined measurements, substantially as described.

- 5 6. An orthopedic last embracing in its construction a last block, a metallic gaging device secured to the bottom thereof and comprising a longitudinal member extending from the rear end of the heel to the
10 middle portion of the ball line of the last, and a transverse member united intermediate of its ends to the said longitudinal member with its ends extended to proper position to indicate according to predetermined
15 measurement the ball points of the last on opposite sides thereof, substantially as described.
7. An orthopedic last embracing in its construction a last block comprising a heel
- part and a forepart movably connected, a 20 gaging device secured to the bottom of said last block and comprising a longitudinal member whose rear end is formed with a vertical extension inserted in the rear end of the heel, and a transverse member united 25 to the forward end of said longitudinal member with its opposite ends located according to predetermined measurements to indicate the correct position of the opposite ball portions of the last, said longitudinal 30 member being sub-divided into two portions at the line of separation between the heel and forepart of the last in order to permit the movement of the heel in relation to the fore-part, substantially as described. 35

In witness whereof I have subscribed the above specification.

ELMER J. BLISS.
